UNITED STATES PATENT OFFICE.

ROBERT C. RINGHOLZ, OF SALT LAKE CITY, UTAH.

PLASTER BOARD.

Application filed August 9, 1922, Serial No. 580,681. Renewed March 10, 1924.

To all whom it may concern:

Be it known that I, ROBERT C. RINGHOLZ, a citizen of the United States, and a resident of Salt Lake City and county, State of Utah, whose address is 349 South 3rd East Street, Salt Lake City, Utah, have invented a new and useful Improvement in Plaster Boards, of which the following, taken in connection with the accompanying drawings, is a specification.

My invention has for its object to provide a plaster-board that will be stronger than the ones made of paper and plaster, and also stronger than one that might be formed with a thin sheet of metal, wire netting or the ordinary metal lath.

A further object is to provide a plaster-board so reinforced that nails may be driven through any portion of the same without breaking the plaster when fastening it to its place on the studs or joists.

My invention has also for its object to provide a metal re-inforced plaster-board in which the metal sheet is cut with dies, and at the same time so pressed that the strips cut into the sheet of metal form curvilinear projections on each side of the metal sheet and form a part of the same, said curvilinear projections being staggered and occurring on the sheet at approximately right angles to each other throughout the sheet, the curved portion projecting alternately on one side and then on the other side of the sheet of metal, causing the same to act as transverse re-inforcements in each of the side sheets of plaster while the body of said metal sheet also acts as a re-inforcement between said sheets of plaster.

These objects I accomplished with the device illustrated in the accompanying drawings in which similar reference letters indicate similar parts throughout the several views.

In the drawings in which I have substantially shown my invention, Figure I is a plan view of a fragment of the board with parts cut away, Figure II is an edge view of the board showing the protruding portions of the flattened curvilinear projections when the plaster sheets have been removed, and Figure III is a plan view of the metal sheet when cut and pressed ready to receive the coating of plaster on either side.

My invention consists of the metal sheet "A" having a plurality of flattened curvi-

linear projections made thereon by cutting approximately parallel lines and pressing the portion in between said cuts outwardly from one side of the sheet, and pressing the portion between the adjacent two cuts to the opposite side of the sheet and staggering these projections so that they will be alternately at right angles to each other when considered as in a plane. The purpose of so displacing and arranging the metal pressed out of the general plane of the sheet is to form arch-like portions of metal alternately, having the arch first on one side and then on the other so as to form an approximately ovate oblong transverse perforation in the plane of the metal sheet through which the plaster may protrude from one side to the other, thus causing the arch-like projections to act as lateral and longitudinal re-inforcements in the general plane of the finished sheet.

The perforated sheet "A" is covered on both sides with plastic plaster "B" of any desired thickness from an eighth of an inch to say a quarter of an inch, which plaster when set adheres to the surface of the metal sheet, fills the ovate oblong perforations and thus unites the sheet of plaster on one side of the perforated metal sheet with the sheet of plaster on the other side of the metal sheet; the two sheets of plaster thus forming a composite whole, re-inforced throughout laterally and longitudinally with alternate convex and concave strips of metal, thus making a very strong plaster-board for its size and weight. The plaster "B" is made of calcined gypsum or any other material which may be applied in a plastic condition and which will set and harden.

In my drawing I have shown the metal cut into strips, forming approximately a Roman arch: It will be understood, however, that these strips may be pressed so as to form a Gothic arch, or so as to form an acute or obtuse angle with straight sides without departing from the spirit of my invention. It will also be understood that these strips may be cut or broken at or near the center, or perforated at or near the center without departing from the spirit of my invention; and also, that while I show and claim the recessions and depressions as being alternately adjacent to each other, that any other arrangement may be made, and that all of the depressions or

recessions may be arranged so that there will be only projections and no recessions immediately adjacent when viewed from one side of the sheet, and while this arrangement would not make the metal reinforcement as strong as where there are projections on each side of the sheet, it might be so used where greater strength was not required.

10 It will also be observed that the drawing shows the metal sheet with or without the edge cut or notched, and the cut portions thereof alternately pressed out of the general plane on the sheet of metal so as to 15 re-inforce the edge thereof and reduce the liability of the plaster cracking or chipping when nails are driven through close to the edge. It will be understood that the edges of the metal sheet may be so treated or not 20 as may be desired.

It will also be observed that the perforated metal sheet above described may be used as an ordinary metal lath and that finely divided concrete mixtures, gypsum 25 mixtures, magnesite mixtures, Keene cements etc., may be also applied in sheets to either or both sides of my perforated metal sheet and thus form a smooth and finished wall, floor or ceiling.

30 It will also be seen that the curvilinear projecting and receding strips may be in the same or another operation bent or corrugated, forming V or U shaped corrugations lengthwise or crosswise of the strips 35 without departing from the spirit of my invention, and where greater strength is re-

quired, it will readily be seen that it may be obtained in this way.

It will also be seen that these curvilinear projecting and receding strips may be bent 40 or pressed at an angle to the plane of the sheet without departing from the spirit of my invention.

Having thus described my invention, I 45 claim:

1. A plaster-board of the class described comprising a metal sheet, having a plurality of alternately adjacent convex and concave projections and recessions cut and pressed therein, leaving approximately ovate 50 oblong perforations in the cross section of the sheet and cover sheets of plaster on both sides of said metal sheet filling said perforations and uniting said cover sheets of plaster through the said cross-section perforations. 55

2. A plaster-board comprising a thin metal sheet having a plurality of alternate adjacent curvilinear projections and depressions cut and pressed therein, staggered in 60 relation to each other so that a portion of the projections and recessions are at right angles to each other, said adjacent recessions and projections forming numerous perforations in the lateral and longitudinal plan of the metal sheet, a sheet of plaster 65 covering the said metal sheet and surrounding the said curvilinear projections and filling the said curvilinear recessions and depressions and adhering to the metal sheet and curvilinear projections and recessions.

ROBERT C. RINGHOLZ.
